DESIGN FOR A FLY SWATTER BLADE

Frank Hawkey, Chardon, Ohio, assignor to The Chardon Rubber Company, Chardon, Ohio, a corporation of Ohio

Application January 21, 1935, Serial No. 54,965

Term of patent 7 years

To all whom it may concern:

Be it known that I, Frank Hawkey, a citizen of the United States, residing at Chardon, in the county of Geauga and State of Ohio, have invented a new, original, and ornamental Design for a Fly Swatter Blade, of which the following is a specification, reference being had to the accompanying drawing, forming part thereof, in which:—

Fig. 1 is a top plan view of a fly swatter blade showing my new design; and

Fig. 2 is an elevation projected from Fig. 1.

I claim:

The ornamental design for a fly swatter blade, as shown.

FRANK HAWKEY.
